UNITED STATES PATENT OFFICE.

LEIGH S. BACHE, OF BOUND BROOK, NEW JERSEY, ASSIGNOR TO BOUND BROOK OIL-LESS BEARING COMPANY, OF BOUND BROOK, NEW JERSEY, A CORPORATION OF NEW JERSEY.

SADDLE FOR SPINNING FRAMES.

1,242,758.

Specification of Letters Patent.

Patented Oct. 9, 1917.

Application filed June 16, 1914. Serial No. 845,866.

To all whom it may concern:

Be it known that I, LEIGH S. BACHE, a citizen of the United States, and a resident of Boundbrook, in the county of Somerset and State of New Jersey, have invented certain new and useful Improvements in Saddles for Spinning-Frames, of which the following is a full, clear, and exact description, whereby any one skilled in the art may make 10 and use the same:

The invention relates to spinning frames and particularly to the saddle which rests upon the drawing rolls. The saddle, so-called, provides a means of tensioning the 15 rolls as is well known to those familiar with the art of spinning.

Ordinarily, these rolls are provided with suitable end bearings and with a center bearing portion. Upon the latter rests the 20 saddle which, being held down as by a stirrup and weight, causes the upper set or the "floating" rolls to bear with a greater or less tension upon the lower set of rolls. The material under treatment passes between the 25 upper and lower sets of rolls.

The parts travel at comparatively high speeds and of necessity there is considerable friction between the rolls and saddle, so that it has been necessary to suitably lubricate 30 the bearing surfaces of the saddle.

It is also necessary to have the saddle adjustable with reference to the rolls and to have the stirrup and its weight adjustable so that the tension upon the several 35 rolls may be modified at will for various classes of work and materials. Ordinarily, three floating rolls are employed but in some instances it is necessary to remove the center roll and therefore the saddle should be provided with features of adjustability such as will make the same saddle suitable for all 40 conditions of roll combinations and interchangeable to different machines.

It is the object of the present invention 45 to accomplish all this in a very simple and effective manner, by providing a saddle of two parts which may be adjusted toward and away from each other and which will be held against lateral displacement.

It is also an object of the invention to 50 provide an arrangement of bearing surfaces upon the saddle which will permit ready adjustment to more or less rolls as requirements demand.

A still further object is to provide an 55 adjustment for the application of the stirrup and weight.

The invention while accomplishing all of the above objects also contemplates utilizing in the formation of the saddle a self 60 lubricating material which will prevent undue friction and screaming, to say nothing of wear of the parts.

Referring to the drawings:

Figure 1 is a view in side elevation with 65 the set of rolls shown in cross section and the saddle in place.

Fig. 2 is a top plan view with the rolls 70 broken away but showing the center bearing and the saddle in place.

Fig. 3 is a perspective view of the male 75 part of the saddle.

Fig. 4 is a similar view of the female part.

Fig. 5 is a cross sectional view through 80 the saddle parts.

It is not new in the art to use a two-piece saddle and such devices have usually been loosely secured with reference to each other. A common expedient is to provide a projecting pin on the under part and a perforation 85 in the overlying upper part. The upper part ordinarily has means for attaching a stirrup and its dependent weight and thus upon which the two sections of the saddle rest.

The pin and perforation prevent displacement of the saddle but permit relative movement thereof to a limited extent. It is quite 90 obvious that with such a construction and arrangement of parts there can be no longitudinal adjustment of the saddle parts relatively to each other and to any desirable degree.

It is one of the principal objects of the present invention to provide for practically universal adjustments and still prevent lateral displacement of the parts.

In the accompanying drawings 1, 2 and 3 100 denote the upper or "floating" rolls and 4, 5 and 6, the lower cooperating rolls. These rolls are all provided with suitable end bearings not specifically shown herein and the floating rolls have center bearings 7, 8 and 9 105 upon which the saddle rests.

The saddle, as illustrated, is preferably made in two parts. The part 10 rests upon

the bearings 8, 9 of the rolls 2, 3 and the part 11 rests upon the bearing 7 of the roll 1, at one end and upon the saddle part 10, at the other end. A stirrup 12, to the lower end of which is applied a suitable tensioning device such as a weight (not shown in the drawings) is hung upon the saddle part 11, and its position in one of the grooves 12^a, 13, 14 determines the relative tension upon the roll 1 and the rolls 2 and 3, said rolls being pressed downward upon the corresponding rolls 4, 5, 6.

The saddle part 10 has bearing surfaces upon its under side so disposed that they will fit upon practically any arrangement of rolls and the part 11 has a bearing surface which fits the forward roll.

In the upper side of the part 10, which might well be termed the female part, there is a longitudinal groove or slot 15, which extends from end to end of the saddle part.

Upon the under side of the part 11 which may be called the male part is a centrally disposed dependent fin or web 16 which fits into the groove 15 of the female part. This fin 16, of the male part is of considerable length and obviously when the parts are in place holds them against lateral displacement.

30 The main bearing between the male part 11 and female part 10 is at 17, upon the under side of the male part at either side of its fin 16 and at 18, 19 upon the upper side of the female part 10 at either side of its groove 15.

It is quite obvious that the male and female parts may be adjusted to any desired degree with reference to each other in a longitudinal direction; the fin 16 resting in 35 different positions along the groove 15.

40 Any adjustment which is made does not prevent the necessary freedom of movement of the male and female parts to permit them to adjust themselves to their respective rolls 45 with a proper disposition of tension.

In fact, any desired combination may be effected by shifting the parts 10 and 11 relatively and adjusting the stirrup 12 into the proper notch of the member 11.

50 The parts ride freely upon each other and yet are held against lateral displacement in any of their adjusted positions and whether a full number or a partial number of rolls are employed as illustrated.

55 In practice, the saddle may be made of any suitable material and of course if made of metal, suitable lubricating ducts are provided to lead a lubricant to the bearing surfaces. It is preferred however to employ

60 a material which will be self lubricating, such, for instance, as a wood or fiber treated and impregnated with a lubricant which will always provide a film of lubricant that will prevent wear and overheating due to 65 friction. By utilizing such a material both

the male and female parts may be made of a homogeneous material which will have the same co-efficient of expansion and will thus provide the most ideal lubricating conditions without complications. The articles 70 may be made at a minimum cost and with a minimum of labor and are of extremely light form.

In my prior Patents, No. 1,077,252 issued Nov. 4, 1913, and No. 1,076,941, issued Oct. 28, 1913, there is disclosed a process of treating material and a bearing treated so that it will give necessary lubrication without throwing oil.

I prefer therefore to utilize such a material of this character in forming my saddle parts. Such a material provides lubrication between the saddle parts and the rolls and between the male and female parts of the saddle.

80 I may, in lieu of the material described in my prior patents, use a wood or fiber impregnated through and through with graphite carried with other lubricating materials. I make no claim herein specifically to the process or method of the material impregnated with graphite as such process and method form the subject matter of a separate application.

Although I prefer to employ materials 95 such as above referred to, I do not wish to be understood as confining my invention to the use thereof as any material may be employed provided provision is made for lubrication. The self lubricating material has 100 many apparent advantages, among which, perhaps the most important is the freedom from throwing oil and soiling the goods and the requirement for constant attention and oiling.

105 The exact form and design of the parts may be deviated from to any desired extent without departing from the spirit or intent of the invention which, in the main, contemplates an adjustable saddle, having practically an unlimited longitudinal adjustment, to fit various combinations of rolls, and with means for preventing lateral or other separation of the parts, when in use; together with adjustability of tension upon the several rolls.

What I claim as my invention and desire to secure by Letters Patent is:

1. A saddle for spinning frames comprising a top saddle member and a bottom saddle member, said top member having on its under side a substantially long, longitudinally extending, dependent fin, bearing surfaces of rectangular cross section, bearing surfaces on the underside of said top member at both sides of said fin, a bottom saddle member provided with a plurality of bearing surfaces for the rolls, and having on its upper side a groove from end to end thereof, said groove conforming to the de- 120
125
130

pendent fin and a bearing surface on either side of said groove coöperating with the bearing surfaces of the top saddle member.

2. A saddle for spinning frames comprising a top saddle member and a bottom saddle member, said top member having on its under side a substantially long, longitudinally extending, dependent fin of rectangular cross section, bearing surfaces on opposite sides thereof and upon the underside of the top member, a bottom saddle member provided with a plurality of bearing surfaces for the rolls, and having on its upper side a groove from end to end thereof, said groove conforming to the dependent fin and with a bearing surface on either side of said groove coöperating with the bearing surfaces of the top saddle member, both of said saddle parts being formed of a homogeneous self-lubricating material, whereby all bearing surfaces between the parts and between the saddle parts and the rolls are self-lubricating.

3. A saddle for spinning frames comprising a top saddle member and a bottom saddle member, said top member having on its under side a substantially long, longitudinally extending, dependent fin of rectangular cross section, bearing surfaces on the underside of said top member at both sides of

said fin, a bottom saddle member provided with a plurality of bearing surfaces for the rolls, and having on its upper side a groove from end to end thereof, said groove conforming to the dependent fin, a bearing surface on either side of said groove coöperating with the bearing surfaces of the top saddle member, and means for adjusting a saddle strap upon the top saddle member.

4. A saddle for spinning frames consisting of a lower saddle member provided with a plurality of bearing surfaces upon its under side, and having a groove of rectangular form extending from end to end along its upper side, an upper saddle member coöperating therewith and having bearing surfaces on its under side, and a rectangular centrally disposed rib on its under side filling the groove of the lower saddle member and of substantial length, said upper saddle member bearing upon the lower saddle member at both sides of the groove and said groove and rib interengaged to permit relative longitudinal adjustment of the parts and prevent lateral distortion thereof.
